THOR RUSTAD, OF ERSKINE, MINNESOTA.

FASTENING MEANS FOR GRAIN DOORS.

Application filed August 3, 1921. Serial No. 489,487.

To all whom it may concern:

Be it known that I, THOR RUSTAD, a citizen of the United States, residing at Erskine, in the county of Polk and State of Minnesota, have invented a new and useful Fastening Means for Grain Doors, of which the following is a specification.

This invention relates to a fastening means for securing doors on grain cars.

10 An object of the invention is to provide a simple and reliable fastening means for grain doors which may be applied without using nails or damaging or weakening the door or door post, and which will also form 15 a brace to prevent bulging of the door.

The invention will be best understood from a consideration of the following detailed description taken in connection with the accompanying drawing forming part of 20 this specification, with the understanding, however, that the invention is not confined to any strict conformity with the showing in the drawing, but may be changed and modified so long as such changes and modifications mark no material departure from 25 the salient features of the invention as expressed in the appended claims.

In the drawing:—

Fig. 1 is a side elevation of a grain car 30 disclosing my improved door in position across the door opening of said car.

Fig. 2 is a plan view of the same.

Fig. 3 is a horizontal section of the door, 35 disclosing a plan view of the adjustable securing means on an enlarged scale.

Fig. 4 is a view in detail partly in section, showing a modification of the fastening means.

In the drawing, 1 designates the side of 40 a grain car having a side door opening 2, door posts 3, and a threshold 4. A door 5 is adapted to extend across the side door opening 2, having its ends 6 in engagement with the inner sides of the posts 3. The 45 door may be made of any material ordinarily used for the purpose, and two or more of the door sections are usually positioned one above the other, as shown.

The simplest form of fastening means for 50 the door is disclosed at the left hand side of Figs. 1 and 2 of the drawing, wherein a bar 7 having an eye 8 at one end is loosely and pivotally connected to the door 5 by means of a staple 9 secured to the door and 55 engaging the eye 8 of the bar 7. The outer end of the bar 7 is adapted to abut the side

10 of the door post 3, the bar 7 thus forming an angle with the door and acting as a brace. This bar is reinforced by flanges 11 and 12 extending in opposite directions 60 from the upper and lower edges, respectively, of said bar.

Near its outer free end, the bar 7 is provided with a notch 13 in its upper edge, in which is adapted to be seated a nut 14 provided with an operating arm 15. A hook 16 having a screw-threaded shank 17 engages the internally threaded opening of the nut 14, the hook itself engaging the staple 9^a secured in the door 5. 70

The nut 14 has a countersunk portion 14^a, thereby providing a space between the nut and the threaded shank 17 of the hook 16, so that the head 17^a located upon the outer end of the shank 17 of the hook 16 may be 75 moved within the countersunk portion. The head 17^a being unable to pass by the internally threaded bore of the nut 14, will prevent the hook 16 from becoming disengaged from the nut 14. 80

It will readily be seen that if both sides of the door were supplied with the fastening means described above, with the bars 7 engaged by the staples 9 at one end and at its other end abutting the side 10 of the 85 door post 3, no provision would be made for different width doors.

Since all doors are not of the same width, it is necessary to provide some form of adjustable means for positioning one of the 90 bars 7 along the door, and this is shown at the right hand side of Figs. 1 and 2, and on an enlarged scale, Fig. 3. I provide a bar 18 slidably and loosely mounted within a slot 19 formed in the door 5. The slidably 95 bar 18 is provided at one end with a perforated lug 20 which is loosely engaged by the hook 16, the perforated lug 20 serving the same function as the staple 9^a previously described. The other end of the bar 18 is 100 likewise provided with a perforated lug 21 which is loosely engaged by a hook 22 formed upon one end of the bar 7, the perforated lug 21 replacing the staple 9 of the locking device at the left hand side. The inner edge of the slidably bar 18 is provided with a lug 23 projecting outwardly and downwardly from a point on the bar 18 near the perforated lug 21. The lug 23 105 is adapted to overhang the edge of the slot 19 in the door 5 to relieve the hook 22 of a certain amount of pressure and also to

110

prevent said hook from cutting into the grain door. A similarly constructed and positioned lug 23^a is located on the opposite edge of the bar 18 and prevents said bar 5 from slipping out of slot 19.

Upon the opposite edge of the bar 18 is formed an angularly-disposed upstanding lug 24, which is adapted to engage any one of the teeth 25 on the rack bar 26, which 10 is secured within the slot 19 of the door. It will be seen that the bar 18 may be adjusted along the slot 19 and held in position by the upstanding lug 24 engaging any one of the teeth 25 of the fixed rack bar 26.

15 Fig. 4 discloses a modification of the screw-threaded hook 16 and the nut 14. A sleeve 27, provided with a counterbore 28 and a screw-threaded portion 29, has a depending hook 30 projecting downwardly from its 20 outer periphery and engaging the staple 9^a. A screw-threaded rod 31 provided with external threads 32 which engage the threaded portion 29 of the sleeve 27, has an operating handle 33 at one end, and at its other end 25 an enlarged portion 34, which is adapted to be seated within the counterbore 28, and this prevents the rod 31 from being withdrawn entirely from the sleeve 27, but nevertheless 30 will permit the threaded portion 32 to engage the threaded portion 29 of the sleeve 27, so that the rod 31 may be moved inwardly and outwardly from the sleeve 27. An annular collar 35 is secured to the rod 31 and is adapted to engage the material around 35 the notch 13 in the bar 7, so that as the rod 31 is rotated, the sleeve 27, engaging the staple 9^a will cause the rod 31 to be drawn inwardly and force the bar 7 inwardly towards the door, causing said bar to more 40 firmly engage at its opposite ends the door and the door post, respectively.

In order to secure the door 5 upon the door posts, the door section 5 is placed across the opening so that its ends will engage the 45 door posts 3, the bars 7 being angularly positioned with respect to the door section 5, as shown in Figs. 2 and 3, and the nuts 14 being located within the notches 13 of the bar 7. When the handles 15 are operated, the nuts 50 14 are drawn up tight upon the bar 7, wedging one end of the bar 7 against the face 10 of the post 3, and the other end forcibly against the staple which is secured to the door section 5.

55 If it be found that the bars 7 extend outwardly and beyond the posts when attempting to position the door, or that the bars 7 will nearly coincide or lie flat upon the door 5, it will be necessary to move the lug 20 of 60 the slideable bar 18 inwardly in order to release the lug 24 from the teeth 25, and either slide the bar 18 inwardly towards the center of the door, or outwardly towards the end of the same, as the case may be, so that the 65 bar 7 may be positioned at the proper angle

with respect to the door 5. As the nut 14 is rotated on the screw-threaded shank 17 of the hook 16, it will be drawn up tight against the bar 7, causing the lug 24 to more firmly engage a tooth 25 of the rack bar 26, and 70 thereby prevent displacement of the bar 18 and preserve the adjustment thereof. It will be noted in this connection, that the greater the pull on the lug 20, the greater the tendency will be for the bar 7 to force the 75 inner end of the bar 18 near the perforated lug 21 inwardly into the slot 19, and the outer free end of said bar in gripping engagement with the side 10 of the post 3, while the lug 24 will more firmly grip one 80 of the teeth 25.

It will be observed that a very secure and efficient fastening means is thus provided, wherein no holes are required to be cut in the post, since the outer free ends of the bars 7 85 merely abut the door posts 3, and the device may be applied or removed instantly without the use of any tools.

What is claimed is:—

1. A door, means loosely mounted at one 90 end on the door and adapted to be inclined at an angle to the door with the other end abutting a door post, and means loosely connected with the door and engaging with the first-mentioned means for wedging the respective 95 ends of said means against the door post and its connection with the door to lock the door in position.

2. A door provided with a slidably mounted means, means pivoted at one end to the 100 slidable means and at the other end adapted to abut a door post, and a second means pivotally mounted on the slidable means and engaging the first-mentioned pivoted means to secure the door in place. 105

3. A door provided with means adjustable longitudinally of the door, a bar adjustable at one end to the adjustable means and at the other end adapted to abut a door post, and a second adjustable means connected to the 110 other end of the first-mentioned adjustable means and engaging the bar for securing the door.

4. A door provided with means adjustable longitudinally of the door, a bar loosely connected at one end to the adjustable means, the other end of the bar being adapted to abut a door post, a second adjustable means loosely connected to the other end of the first-mentioned adjustable means and engaging 120 the pivoted bar at an intermediate point of its length for securing the door, and means for retaining the first-mentioned adjustable means in position.

5. A door provided with means adjustable longitudinally of the door, a bar connected at one end to the adjustable means, the other end of the bar being adapted to abut a door post, and a second adjustable means connected to the other end of the first-men- 125 130

- tioned adjustable means and engaging the pivoted bar at a point between its ends for securing the door, the first-mentioned adjustable means being provided with a lug 5 which is adapted to engage one of a series of teeth on the door to lock the first-mentioned adjustable means in position.
6. A car door, means connected at one end to the door and extending outwardly at an 10 angle to said member and abutting at the other end a door post, and means loosely connected with said door and engaging the first-mentioned means at a point between its ends to secure said door to the car.
- 15 7. A door, means pivotally connected with the door and engaging a door post, and means connecting the door with the pivotally mounted means at a point between the ends of said pivoted means.
- 20 8. A door, a bracing means for the door to prevent bulging of the door, and means loosely connected with the door and engaging the bracing means and cooperating therewith to lock the door in position.
- 25 9. A door, a bar pivotally mounted on the door and abutting a door post, a hook loosely connected with said door and provided with a screw-threaded shank, and a nut adjustable on the threaded shank of the hook and 30 engaging the bar to force the free end of the bar into engagement with the door post to lock the door.
- 35 10. A door, an adjustable bar slidably mounted in a slot in the door, a bar pivotally connected at one end to an end of the adjustable bar and having its free end in abutting relation with a door post, a hook loosely connected with the other end of the adjustable bar, means on the hook and en- 40 gaging the pivotally mounted bar for drawing the door towards the pivoted bar, and means on the adjustable bar and engaging the door to prevent displacement of said bar from the slot in the door.
- 45 11. A door, an adjustable bar slidably mounted in a slot in the door, a bar pivotally connected at one end to an end of the adjustable bar and having its free end in abutting relation with a door post, a hook loosely connected with the other end of the adjustable bar, means on the hook and en- 50 gaging the pivotally mounted bar for drawing the door towards the pivoted bar, a rack bar secured in the slot of the door, and means on said adjustable bar adapted to engage the rack bar to prevent displacement of the adjustable bar.
- 55 12. A door, an adjustable bar slidably mounted in a slot in the door, a bar loosely connected at one end to an end of the adjustable bar and having its free end in abutting relation with a door post, and means having connection between one end of the adjustable bar and the pivoted bar and adapted to exert a pull between said bar 60 tending to force the ends of the adjustable bar in opposite directions.
- 65 13. In a door, a bar having its ends engaging respectively the door and a door post, an internally threaded sleeve provided with a counterbore concentric with but larger in diameter than the threaded bore, a screw-threaded rod engaged in the threaded bore, and having a flared end located within the counterbore, and means connecting the combined sleeve and rod with the bar and door, said sleeve and rod being rotatable relative to each other to lock the door to the door posts.
- 70 14. In a door, a bar having its ends en- gaging respectively the door and a door post, an internally threaded sleeve provided with a counterbore concentric with but larger in diameter than the threaded bore, a hook depending from the end of said sleeve 80 and engaging a staple mounted on the door, a screw-threaded rod engaged in the threaded bore and having a flared end located within the counterbore, means on the other end of said rod for rotating the same, and 85 means on said rod adapted to engage the bar to draw the door up firmly to the door post when said rod is rotated.
- 90 In testimony, that I claim the foregoing as my own, I have hereto affixed my signature.

THOR RUSTAD.
